UNITED STATES PATENT OFFICE.

FRED G. ROCKWOOD, OF MENDOTA, WISCONSIN.

QUICK-ACTING WRENCH.

1,156,932.

Specification of Letters Patent. Patented Oct. 19, 1915.

Application filed February 6, 1915. Serial No. 6,510.

To all whom it may concern:

Be it known that I, FRED G. ROCKWOOD, a citizen of the United States, residing at Mendota, in the county of Dane and State 5 of Wisconsin, have invented certain new and useful Improvements in Quick-Acting Wrenches, of which the following is a specification, reference being had to the accompanying drawings.

10 My invention relates to wrenches, and particularly to wrenches of that type wherein the movable jaw of the wrench is shiftable quickly into approximate position and afterward tightened by means mounted upon 15 the handle of the wrench.

The primary object of my invention is to provide a wrench so constructed that it may be readily applied and may be used either as a pipe wrench or as an ordinary wrench.

20 A further object of the invention is to so construct the wrench that the parts are compactly arranged, may be readily assembled, and may be easily operated.

A further object of the invention is to provide 25 a wrench of the character described wherein a movable jaw is freely shiftable upon guide rods forming part of the handle shank and is locked in position by a shaft having thereon interrupted screw threads, 30 the shaft being contained entirely within the shank or handle of the wrench.

Other objects will appear in the course of the following description.

My invention is illustrated in the accompanying drawings, wherein—

Figure 1 is a side elevation of a wrench constructed in accordance with my invention, showing the actuating shaft turned to its operative position; Fig. 2 is a section on 40 the line 2—2 of Fig. 1, but showing the actuating shaft in its inoperative position; Fig. 3 is a section on the line 3—3 of Fig. 1, also showing the shaft in its inoperative position.

45 Referring to these figures, 2 designates the fixed jaw of the wrench and 3 generally denotes the handle shank, which terminates in the handle 4. The handle shank 3 comprises a pair of oppositely disposed parallel 50 spaced members relatively narrow, each having flat sides, a curved outer face and a convexly curved inner face 5. These members 3 are connected to a solid portion of the shank designated 6, which is preferably integral with the jaw 2 and which is formed 55 with a central bearing socket 7.

Mounted upon the shank formed by the members 3 and longitudinally slidable thereon is the movable jaw 8 which is formed with an opening to receive the shank members 3, 60 as clearly shown in Fig. 2, this opening being designated 9. The lateral walls of the opening are formed with interrupted screw threads 10 concentric to the axial center of the shank of the wrench. 65

Disposed between the members 3 is an actuating shaft 11 whose extremity is reduced and pointed and is supported in the socket 7, this extremity being designated 12. The two side faces of this shaft 11 are flat while 70 the edge faces of the shaft are formed with the interrupted screw threads 13 adapted to engage with the interrupted screw threads 10 of the jaw 8. The shaft 11 is rotated by and is operatively mounted upon a knurled 75 collar 14, as clearly shown in Fig. 3. This collar is provided with inwardly extending diametrically disposed screws 15 which pass through the knurled collar and into the butt end of the shaft 11. The knurled collar 14 80 has sufficient rotation to carry the shaft 11 through a quarter revolution so as to either engage the threads of the shaft with the jaw 8 or to dispose the threads of the shaft in the inoperative position shown in Figs. 85 2 and 3, whereupon the jaw 8 will be freely shiftable upon the shank 3. It will be noted that the screws 15 form stops for limiting the rotation of the shaft 11 to a quarter turn 90 in either direction.

Preferably the jaw 2 and the jaw 8 extend at both ends beyond the shank, the jaws at one end being provided at their inner faces with the reversely inclined teeth 16 and the inner faces of the opposite ends of the jaws 95 being smooth. Thus the teeth 16 are adapted to engage a pipe, rod or other cylindrical member which it is desired to rotate, while the other ends of the jaws are adapted to engage the facets of a nut or like element. 100 Preferably also the jaw 8 is formed with a bracing portion 17 which extends outward along the face of the adjacent shank member 3 so as to steady the jaw in its movement.

My improved wrench is adapted to a large 105 variety of uses, as will be obvious. It will also be obvious that the wrench may be very cheaply constructed and may be easily assembled, and that it is very effective in action. It is a relatively easy matter to adjust the sliding jaw 8 to the work to be operated on and then to clamp this jaw firmly 110

in position and bring it up tightly against the work by rotating the knurled collar 14 and the shaft 11. It will be seen that with simply a quarter turn to the right the movable jaw 8 is released so that it may be shifted either forward or backward to fit any sized nut within the capacity of the wrench.

It will be seen that my invention is very simple, thoroughly effective for the purpose intended, and may be sold at a relatively low cost. The shaft 11 is entirely housed between the members 3 and therefore will not be damaged in use. As soon as the screws 15 are removed the shaft 11 may be readily removed by shifting the knurled collar 14 along the handle portion 4 and withdrawing the shank.

Having described my invention, what I claim is:

20. A wrench comprising a handle shank having a solid portion, a jaw mounted thereon, longitudinally extending parallel portions

and a handle, the solid portion being formed upon its inner face with a socket, a shaft disposed between said parallel portions and having a prolongation bearing in said socket, the shaft having oppositely disposed interrupted screw threaded faces, a collar mounted upon the shank adjacent the handle thereof and having screws engaged with the 25 shaft, said screws acting as stops limiting the collar to a quarter turn, and a movable jaw mounted upon the handle shank for sliding movement and having oppositely disposed interrupted screw threaded faces 30 adapted to be engaged with the screw threaded faces of the shaft upon a quarter turn of the shaft in one direction.

In testimony whereof I hereunto affix my signature in the presence of two witnesses. 40

FRED G. ROCKWOOD.
